GAME BOARD

Cecil B. Woofter, Crystal, Minn., assignor of one-half to
Donald E. Harley, St. Paul, Minn.

Application March 8, 1955, Serial No. 34,950

Term of patent 14 years

(Cl. D34—5)

Figure 1 is a plan view of the game board showing my new design.

Figure 2 is a side elevational view of that game board.

Figure 3 is a front elevational view of that game board.

Figure 4 is a cross-sectional view of that game board along line 4—4 of Figure 1.

Figure 5 is a cross-sectional view of that game board along line 5—5 of Figure 1.

Figure 6 is a cross-sectional view of that game board along line 6—6 of Figure 1.

Figure 7 is a cross-sectional view of that game board along line 7—7 of Figure 1.

I claim:

The ornamental design for a game board, as shown.
